UNITED STATES PATENT OFFICE.

JAMES C. ANDERSON, OF HIGHLAND PARK, ILLINOIS.

BRICK AND TILE MACHINE.

SPECIFICATION forming part of Letters Patent No. 276,549, dated May 1, 1883.

Application filed February 19, 1883. (No model.)

To all whom it may concern:

Be it known that I, JAMES C. ANDERSON, a citizen of the United States, residing at Highland Park, in the county of Lake and State of Illinois, have invented certain new and useful Improvements in Brick and Tile Machines, of which the following, when taken in connection with the accompanying drawings, forms a full, clear, and exact description.

Referring to the drawings, Figure 1 is a side elevation of a portion of the machine. Fig. 2 is an end view of a portion or one side of the machine. Fig. 3 is a sectional view of a portion of the machine, showing the plungers withdrawn from the brick. Fig. 4 is a side view of the operating-cams. Fig. 5 is a front view of the same. Fig. 6 is a sectional rear view of the lower portion of the machine, showing the bearings and toggle-lever of the lower plunger. Fig. 7 is a view in perspective of the main driving-shaft and cams for moving the operating parts, as will more fully hereinafter appear. Fig. 8 is a front elevation of a completed machine as ready for operation.

My present invention is designed as an improvement in certain operating parts of the machine which was patented to me March 11, 1879, No. 211,085, and relates more particularly to the mechanism for producing an under pressure upon the brick, and to mechanism for discharging or forcing the finished bricks out of the molds.

In describing my present invention I shall refer to such parts only of the patented machine as are necessary to give a correct understanding of the present invention, the mold-wheel and devices for operating the same, the clay feeding and measuring devices, the brick-lifting devices, the frame of the machine, together with the main plunger and the gearing for operating the machine, being in all essentials the same as in the patent above referred to.

A A indicate two castings, secured together at a suitable distance apart by means of screw-bolts, and mounted on a suitable foundation. The castings A A form the main frame of the machine, in which the driving-shafts and other operating parts are mounted, and upon which the superstructure of the machine is built.

a is a stirrup or bed, formed of a steel casting, firmly secured in the lower portion of the

frame or castings A A by means of lugs a', which have their bearing upon corresponding shoulders or offsets, a'', formed in the frame or castings A A, the office of which is to provide a fulcrum or firm bearing for the toggle-levers, which operate the lower plunger.

A' is the lower pressure-plunger, which is free to work in ways formed in the casting A'', which is firmly secured to the side castings or frame, A A, by means of lugs or bolts b b. The lower end of the plunger A' is pivotally secured to the member b' of the toggle-lever B, while the other member, b'', of the toggle is seated in bearings formed in the stirrup or bed a by means of lugs cast on the arm or member b'', which are seated in cavities or boxes formed for that purpose in the stirrup a. The central portion of the toggle-lever is connected to the rock-shaft B' by means of the arms c c, the rock-shaft B' being seated in bearing in the frame of the machine and operated by mechanism, to be hereinafter described, so as to give to the plunger a reciprocating motion in a vertical direction. The position of the plunger A' is in a central vertical line above the axis of the arm b'' of the toggle-lever and centrally to the mold-cavities of the mold-wheel C, which brings this plunger immediately under one of the lower die-matrices when the mold-disk is at rest.

C' is a bracket-casting secured to the frame or castings A A, to the upper end of which is secured a plate, C'', which projects over the edge of the mold-wheel and prevents the upward thrust of the lower plunger from raising the mold-wheel.

D is a rocking arm or bar, of heavy steel, rigidly secured to the one end of the rock-shaft B', the ends of which are recessed to provide seats for the longitudinally-sliding boxes h. Said boxes, by their motion in the recesses, compensate for the diverging lines of motion between the vertical thrust of its actuating arm or bar H at the one end and the vertical course of the ejecting-plunger D' at the other end, said ejecting-plunger being guided and steadied to its work in a vertical direction only in ways or guided in bracket-casting D''. The studs d d' of the sliding boxes h in the rocking arm D are firmly secured to the connecting-rod or arm H and ejecting-plunger D', respectively, and made to

work freely in the boxes. The vertical arm or connecting-rod is provided at its upper end with shoulders, which form beds or seats for the gibbs n' n^2 , and also with a vertically-elongated slot, e' , into which is fitted a sliding box, through which box the main driving-shaft E' passes, and by which means the connecting-rod or arm H is held firmly in its vertical position and admits of a proper vertical motion 10 being imparted to it by means of a cam or cams secured to the main driving-shaft E' . The lower end of the connecting-rod H is guided in ways formed in the casting or bracket E^2 .

15 F is a brace-rod, the upper end of which is secured by a proper journal-box to this main driving-shaft E' . The lower end of the brace-rod is bifurcated, one arm of which is secured to the rock-shaft B' , while the outer arm is secured to the frame-work of the machine. The office of this brace-rod is to sustain part 20 of the divergent strain on the main driving-shaft which arises from the force exerted to work the lower plunger, and also the ejecting-25 plunger, through the medium of the connecting-rod H .

The main driving-shaft E' and cam F' , for operating the upper plunger, are essentially the same in construction and movement as 30 described in my patent above referred to, except as to the cams G' G^2 of this shaft, which are the operating-cams of the new or improved mechanism.

The top and bottom gibbs, n' , are secured to 35 the shoulders of the connecting-rod H at a distance apart equal to the largest diameter of the cam G' , forming a housing for this and bringing the gibbs in working proximity to the top and bottom face of the cam, maintaining 40 such proximity to the lower gib during the full revolutions of the cam and to the top gib for that part of the peripheral outline of this cam which coincides with the peripheral outline of the cam G^2 , while the cam G^2 , having a bearing only against the top gib, n^2 , maintains such bearing or contact with this gib during its 45 entire revolutions.

By reference to the patent named it will be seen that the upper plunger automaton or set 50 of movements are positive in their nature, being induced or impelled by a single cam, such cam being spanned by a housing and of such peripheral outline as to admit of a continuous working-bearing against both the top and bottom gibbs.

In operating the peculiar automaton requisite in the new part for giving the under pressure and ejecting the brick from the molds in conjunction and time with the upper plunger 60 movement, this method could not be adopted in the new part, as the cam for this part must be considerably elongated to actuate and complete its movements in the proper time with the top plunger, as evidenced by the fact that 65 the top plunger is made to descend well in advance of the arm or connecting-rod H of the new movement, while the full molding op-

eration must be completed and the several plungers withdrawn to clear the mold-disk at the same time. I have therefore provided in 70 connection with this cam the cam G^2 , having a peripheral outline contorted to represent the exact vertical movement of the arm H . This cam, being provided with a top gib-bearing only, serves practically as a lifting and 75 holding cam to the arm, while the cam G' imparts the downward thrust to the arm H for exerting the pressure. By this method a positive and powerful intermittent vertical motion is given to the arm H , by which a rocking motion is imparted to the arm D to eject 80 the newly-formed brick, and also to the rock-shaft B' , by which the under pressure is operated. This motion, being actuated by the main shaft and conveyed direct to the rock-shaft by 85 means of the connecting-rod or arm H , is practically free from lag or backlash, and insures uniform and perfect movement to all the parts.

The operation of my machine is as follows: The mold wheel or disk C having been rotated 90 to its point of rest by devices essentially such as are shown and described in my patent above referred to, the main driving-shaft E' being rotated in the direction of the arrow, Fig. 3, the upper plunger is made to descend into the 95 mold-cavities f by the impelling force of the cam F' . The arm or connecting-rod H is not allowed, however, to descend to operate the ejecting or the under pressure plunger until the upper plunger or die has entered well into the mold-100 box and the clay powder therein is pressed to a considerable degree of hardness, so that the pressure thus exerted may counterbalance as much as possible the upward thrust of the brick-ejecting plunger. The under pressure-plunger, A' , must be operated against the movable bottom f' of the mold at a point when the upper plunger has commenced its second descent, it being understood, however, that at this point the upper plunger has first descended to 110 within one-fourth of an inch of its fall throw, then receded three-sixteenths of an inch to allow the air to escape from the molds, then again to be depressed one-fourth of an inch, when the lower pressure-plunger is brought 115 into play against the die f' ; and in order to compensate for this latter time of contact between the ejecting and the under plunger propelled at the same time, the plunger A' is allowed to travel through a space, g , before coming in contact with the movable bottom f' of the mold. During this period of contact the 120 movable bottom is forced upward about five-sixteenths of an inch, completing in the one operation its full upward movement, after 125 which movements both the upper and lower plungers remain at rest for a short period of time. By thus holding the pressure upon the mass for a time a more effectual bond takes place between the several atoms of the clay 130 powder, and a portion of the remaining air compressed in the last-described movement is allowed to force its way out of the molds.

The main portion of my machine I prefer to

make of steel castings, so that it will bear the heavy strain put upon it in operation, while the gibs and the portions of the machine which are most exposed to the abraiding influence of friction I make of phosphor-bronze.

Having thus described my invention, what I claim, and desire to secure by Letters Patent, is—

1. In a machine for pressing brick and other material, an upper plunger adapted to exert a variable pressure on the clay, an under plunger adapted to exert a uniform pressure on the movable bottom of the mold, and means, substantially such as described, for operating the plungers.

2. The combination of an upper and lower plunger or die movement, substantially such as described, for removing the atmospheric air in the operation of molding the brick or tile and holding the pressure on the same for a time for cementing and fixing the bond.

3. In a brick-machine, the upper pressing-plunger and main operating-shaft, provided with the cams, as set forth, in combination with the connecting-rod H, rocking lever D, and ejecting-plunger D'.

4. In a brick-machine, the upper pressing-plunger and main-operating shaft, provided with cams, as set forth, in combination with

the rocking lever D, rock-shaft B', arms c c, 30 toggle-lever B, and plunger A'.

5. The combination of the cams G' G², gibs n' n², with the arm H, and pivoted bar D, whereby an intermittent reciprocating motion is imparted to the lower pressure-plunger and 35 to the ejecting-plunger, as set forth.

6. The combination of the stirrup or bearing a, members or links b' b², and plunger A' with the arms or links c c and rock-shaft B', as and for the purpose set forth.

7. The main driving-shaft E', provided with the cam G', in combination with the connecting-bar H, provided with the gibs n' and slot e', and the rocking lever D, as and for the purpose set forth.

8. The bracket C' and cap C², secured thereto and projecting over the edge of the mold-wheel, whereby the mold-wheel is steadied and held in place during the action of the under pressure-plunger.

9. The driving-shaft E', provided with the cams F' G', in combination with the upper plunger, the connecting-rod or arm H, and the rocking arm D.
